UNITED STATES PATENT OFFICE.

EMIL STAHL, OF HOBOKEN, NEW JERSEY.

DESIGN FOR A BEER-COOLER.

SPECIFICATION forming part of Design No. 28,935, dated June 28, 1898.

Application filed June 2, 1898. Serial No. 682,403. Term of patent 7 years.

To all whom it may concern:

Be it known that I, EMIL STAHL, a citizen of the United States, and a resident of Hoboken, in the county of Hudson and State of New Jersey, have invented and produced a new and original Design for Beer-Coolers, of which the following is a specification, reference being had to the accompanying drawings, forming a part thereof.

10 The leading feature of my design consists in a beer-cooler comprising a cylindrical outer wall, a concave bottom, and a conical inner wall having its larger diameter near the open end of the cylindrical outer wall and its

15 smaller diameter at the concave bottom.

In the accompanying drawings, Figure 1 is a side view of the cooler. Fig. 2 is a vertical

central section through the same, and Fig. 3 is a top plan view.

The cylindrical outer wall is denoted by A, 20 the concave bottom by B, and the conical inner wall by C.

What I claim is—

The design for a beer-cooler substantially as herein shown and described. 25

In testimony that I claim the foregoing as my invention I have signed my name, in presence of two witnesses, this 27th day of May, 1898.

EMIL STAHL.
